UNITED STATES PATENT OFFICE.

HERMAN FRASCH, OF NEW YORK, N. Y., ASSIGNOR TO STANDARD OIL COMPANY, OF BAYONNE, NEW JERSEY, A CORPORATION OF NEW JERSEY.

SEPARATING LOW-BOILING PRODUCTS FROM THE BURNING-OIL DISTILLATE OF PETROLEUM TO RAISE THE FIRE TEST THEREOF.

No. 845,456.

Specification of Letters Patent.

Patented Feb. 26, 1907.

Application filed August 11, 1900. Serial No. 26,648.

To all whom it may concern:

Be it known that I, HERMAN FRASCH, a citizen of the United States, residing at the city of New York, borough of Manhattan, county of New York, in the State of New York, have invented certain new and useful Improvements in Separating Low-Boiling Products from the Burning-Oil Distillate of Petroleum to Raise the Fire Test Thereof, and I do hereby declare the following to be a full, clear, and exact description of the invention.

This invention relates to the separation from the burning-oil distillate of petroleum of those portions which on account of their volatility (or low boiling-points) are liable to form explosive mixtures with air at, comparatively speaking, low temperatures, or, in other words, it relates to raising the fire test of burning-oil distillate.

In the fractionation of the crude petroleum by distillation the operation can be so conducted as to give burning-oil distillate having as it comes from the end of the condenser the fire test desired; but in so proceeding, prior to the recovery of this high-test distillate, there would be received a product too light to be burned in a lamp and too heavy for use as naphtha, (benzin,) yet containing desirable portions of burning oil and naphtha. It has been the practice, therefore, to commence the collection of distillate for burning oil while yet the more volatile constituents of the crude oil are coming over, and to resort to a supplementary distillation to remove these constituents, or, in other words, to raise the fire test of the burning-oil distillate. The particular points at which the collection of this distillate shall begin and end and in what manner the distillation is to be conducted are determined by the judgment of the manufacturer, according to the character of the products which he is making and other considerations, and he may of course collect the said distillate in fractions, one or more of which would be of the proper fire test as the same came from the condenser and these could be mixed with the remainder of low fire test after this has been deprived of its more volatile constituents; but in practice all the distillate for the particular grade of burning oil being

manufactured is collected or mixed together and subjected to the operation for raising the fire test.

The present invention relates to the separation of the more volatile constituents from the whole or any desired fraction of such distillate.

At first resort was had to a partial distillation by fire heat in order to raise the fire test; but while this was effective in this regard in using fire under the still the boiling-point of the more volatile constituents was so high that a polymerization set in with an accompanying coloring of the distillate, which made the subsequent treatment with acid very difficult. In fact, some oils subjected to such supplementary fire-distillation could not be made white at all. To remove this difficulty, the supplementary distillation for fire test was effected by steam, the distillate of low test being brought into contact with free steam. Various processes and apparatus have been proposed at various times for such steam-stilling; but the current procedure prior to my present invention was as follows: The low-test distillate was placed in a large still, having a capacity in large refineries of from two thousand five hundred to four thousand barrels, and provided with steam-coils, some of them closed so as to raise the temperature by dry heat and others perforated to allow free steam to enter the oil. The still was also provided with a small rectifying-column, through which the vapors passed on their way to the condenser. When the still was filled, the steam was let on at first into the closed coils and then into the perforated coils also and the heating and steaming were continued until the distillate was brought to the proper fire test, which, in the case of the large stills above mentioned, would take about two days. Then the distillate had to be cooled down preparatory for treatment with acid, the still was refilled, and its contents heated and steamed as before. During the steam-stilling the steam would carry over more or less of the burning oil, which would be recovered by the rectifying-column and returned to the still. This procedure is objectionable as well because the prolonged subjection of the distillate to the temperature of the steam makes the

color somewhat darker and the distillate harder to treat with acid, as also because a great deal of time is lost and heat wasted.

In accordance with the present invention the low-test burning-oil distillate is subjected to free steam, with or without being exposed at the same time to the dry heat of closed coils, and the resulting vapors are brought into repeated contact with a stream, more or less broken up and diffused, of preliminarily-heated low-test distillate mingled with hot water, the said stream constituting the supply of distillate to be raised in fire test, or at least a substantial part of such supply, and being heated most advantageously by heat derived from the hot high-test distillate from which the more volatile portions have been separated and the hot water with which the said stream of distillate is mingled being the water of condensation from nearly the whole (or at least from the chief portion) of the injected steam. The water which returns along with the stream of distillate is separated by settling and decantation within the still or in an outside receptacle. By this process in order effectively to drive off the low-boiling products, which may constitute twenty per cent., more or less, of the low-test distillate, this latter need be kept at a steam heat only for a short time, (under two hours—steaming for a few minutes, not over fifteen, having, in fact, given excellent results,) so that the alteration in color can be reduced to a minimum, and, in fact, becomes hardly perceptible, (if perceptible at all.) Thus to shorten the time of steaming the volume of distillate is limited relatively to the volume of steam admitted thereinto, (such limitation being itself a special feature of invention;) but it follows from this concentration of the energy of the steam on so small a volume of distillate that the resulting vapors contain much more burning oil than those given off from the very much larger volume of distillate subjected to steam in the procedure indicated above. By bringing these vapors repeatedly into contact with the stream of preliminarily-heated low-test distillate mingled with hot water there takes place a fractional condensation which causes most (if not all) of the burning oil to become condensed and united in said stream of distillate, while allowing the more volatile constituents (low-boiling products) to pass away and, if necessary or desired, the vapors can be subjected to further cooling, with the object of collecting any remaining portions fit for burning oil or of separating the vapors into various grades of naphtha.

The preliminary heating of the low-test distillate is important in order that it may not condense the low-boiling products. Practically a temperature of about 170° Fahrenheit will be suitable for raising the distillate to 150° Fahrenheit fire test and can

be obtained by recovery of heat from the high-test distillate hot from the steaming operation; but a less or even a greater degree of preliminary heating can be resorted to. There are advantages in having the low-test distillate heated to about or above the fire test desired, preliminarily to bringing it in contact with the vapors, and such heating is regarded as a special feature of invention; but the use of a materially-lower degree is not excluded altogether. The presence of the considerable volume of hot water is also important in equalizing the heat, by reason of its high specific heat, and in modifying the condensing operation, by reason of its unlikeness to oil in its chemical properties. The contact of the vapors with the stream of distillate not only has the effect of condensing a portion of the vapors, (including the steam,) but also of evaporating a portion of the said distillate, so that the heat of the condensed vapors is utilized in aiding the distillation. By the present invention, therefore, an improved high-test distillate is obtained with less expenditure of time and heat than by the current procedure indicated above.

In subjecting the distillate to the free steam they may be brought together in any ordinary or suitable way, even in the same manner in which said distillate and the oil-vapors are brought into contact with each other; but it is an advantage and special improvement to admit the free steam into a traveling body of distillate at intervals in its line of travel, the said body being supplied by a stream of distillate to be steamed at one end and discharging in a stream of steamed distillate at the other. Moreover, it is of further advantage (and special improvement) to divide said traveling body into a succession of two, three, or more communicating pools and to make said pools diminish in depth, so that the removal of the last portions of the low-boiling products takes place from a shallower layer than that (or those) from which the earlier portions are removed and that consequently there is less danger of retaining low-boiling products in the distillate. So far as I am aware it is new to steam low-test burning-oil distillate in this way irrespective of what may be done with the resulting vapors, and such steaming is therefore included as an essential element in some, although not in all, of my claims. Moreover, I believe it to be new to raise the fire-test of burning-oil distillate by subjecting the latter to free steam and bringing the resulting vapors into repeated contact with a stream of distillate mingled with hot water, even if the said distillate consist only or substantially of the products of the fractional condensation of said vapors. In such case the supply of low-test distillate, where it would not exert a condensing action upon the vapors, might with less detriment be introduced without

preliminary heating, since it would become heated by the steam; but, nevertheless, it would lessen by so much the evaporating power of the steam, and it is advantageous to heat it preliminarily, especially if such heating be effected in cooling the steamed distillate.

As thus far described my invention has been set forth as one relating to raising the fire-test of burning-oil distillate; but the same involves also processes of more general application—that is to say, to the distillation of oily liquids, especially those containing petroleum-naphtha along with heavier liquids for the removal of the naphtha therefrom, and still more broadly to the distillation of liquids in general. As these more general processes are illustrated by the special processes above described for raising the fire-test of burning-oil distillate, it will suffice to refer to the hereinafter-written claims for pointing them out.

In the accompanying drawings, which form part of this specification, Figure 1 is a diagram in elevation of apparatus suitable for carrying the invention into effect. Fig. 2 is an elevation, partly broken away and partly in vertical section, of a portion of the heat-exchanger belonging to said apparatus. Fig. 3 is a vertical section, partly broken away, of one of the elements of said exchanger, the section being in a plane transverse to that of Fig. 2. Fig. 4 is a plan of a portion of the heat-exchanger. Fig. 5 is a vertical section, partly in elevation and partly broken away, of the horizontal still, distilling and rectifying column, and rectifier belonging to said apparatus. Fig. 5^a is a detail view illustrating a feature of said horizontal still. Fig. 6 is a transverse section of the horizontal still; and Fig. 7 is a detail view showing two water-discharge pipes for this still, either of which pipes can be used.

The apparatus as a whole consists, as shown, of a distilling and rectifying column A, having a supply-pipe 2 opening into its upper part, a rectifying-column B, discharging its products of condensation into the upper part of said column A, a horizontal still C, which receives the liquids from said column A and is provided with closed steam-coils 3 and perforated steam-coils 4 and also with a draw-off 5 for the water, and a heat-exchanger D connected with the outlet from still C by the pipe 6^b, drainage-tank G, pipe 6^a, pump E, and pipe 6, and with the upper part of the column A by said pipe 2. The heat-exchanger is provided with an outlet 7 for the high-test distillate and an inlet 8 for the low-test distillate, whose fire test is to be raised in the column A and still C and which is preliminarily heated in the heat-exchanger D by taking up the heat from the high-test distillate, and so cooling the latter on its way through the heat-exchanger. The pumps E

and F move the high-test and the low-test distillate, respectively, in opposite directions through the heat-exchanger. The small pipe 6' is for equalizing the pressures in the still C and tank G.

The rectifying-column B is shown provided with a jacket 9, having pipes 10 and 11 for introducing and carrying off a cooling liquid. It may be water or any other cooling liquid. A special jacket, however, is not essential to the rectifying action, since it suffices for this that the vapors are repeatedly brought in contact with returning condensate from higher parts of the rectifying-column.

At 12 is an additional supply-pipe entering the upper part of the rectifying-column B for discharging distillate thereinto when desired. It can be usefully employed, for example, in filling the apparatus with high-test distillate in starting, or it can be used to introduce low-test distillate then or during the operation, the distillate in either case being preliminarily heated or not as the case may be. The vapor-outlet 13 from this rectifier B can be connected with an ordinary condenser (not shown) or with other appliance or appliances which have heretofore been connected with the vapor-outlets of stills, and will therefore suggest themselves.

The columns A and B are divided, as shown, into a number of chambers by horizontal partitions 14, which are perforated and provided each with a pipe 15 and bell 16 and overflow-pipes 17. The vapors rising through the pipes 15 are by the bells 16 brought repeatedly into contact with liquid, which forms a layer on each partition above the edge of the bell and flows from chamber to chamber through the pipes 17. This is a common structure of column in arts which employ rectifying, distilling, or absorbing columns. It forms no part of the invention and can be replaced by any known or suitable arrangement for bringing vapors and liquids repeatedly into contact with each other as they pass through the apparatus. Numerous arrangements of this description are known in various chemical industries.

The still C, as shown, holds a body of liquid which travels (or flows) horizontally at an appropriate speed through the same, being supplied at one end by the stream from the column A through the lowermost pipes 17 (or by any other suitable connection, if preferred) and discharging in a stream at the other through the pipe 6^b. At intervals are dams or partitions 18 to divide the traveling body of liquid into a succession of pools, which communicate by overflowing one into the other. This separation into pools aids in keeping the different parts of the body of liquid, which have been subjected to different degrees of steaming, better separated from one another. By making the dams or

partitions 18 diminish in height toward the outlet 6^b the further advantage, as above explained, is secured of having the horizontally-traveling body of liquid diminish in depth as it approaches said outlet 6^b.

The water which is delivered with the oil from the column A settles to the bottom of the still C and if not otherwise disposed of would fill the pools to the tops of the dams 18. To allow it to pass from one pool to the next, each dam (except the last) is provided at the bottom with an opening 19, (see Fig. 5^a;) but other arrangements could be provided for its conveyance, if preferred. From the pool next the outlet 6^b the water can be discharged by the draw-off 5, which is provided, as shown, with a swinging arm 20, that can be turned to raise or lower its open outer end, and so determine the depth at which the layer of water under the distillate shall stand.

In each compartment of the still C, except the small one drained by outlet 6^b, are a closed steam-coil 3 and a perforated coil 4. The closed coil is supplied from the main with exhaust-steam from engines used to supply power at the works or from other sources (or it may be with live steam or both live and exhaust steam) and discharges into the drain-pipe 22. The perforated coil is supplied from the main 23 with live steam, (or it may be with exhaust-steam or with both live and exhaust steam.) By "perforated coil" is to be understood any appropriate device for introducing free steam into the distillate. As shown, these coils consist of a number of straight pipes. They are perforated on the under side with holes, which may be an eighth of an inch in diameter and one foot apart, so as finely to divide the entering steam.

The heat-exchanger D consists, as shown, of a number of connected elements, as many of these being used as may be judged useful to transfer the heat from the outgoing high-test to the entering low-test distillate, say ten, such as shown for the apparatus represented, although for lack of space only nine are indicated. Each element (see Figs. 2 and 3) resembles a tubular boiler or condenser in that it consists of a number of tubes 24 between the partition-plates 25 of a shell 26. The shell is thus divided into two compartments or chambers by the partitions and the tubes, and the compartments are connected by the pipes 27 and 28 into two series, so that the high-test distillate starting at one end of one series may pass over one surface of the tubes, (outside or inside, as the case may be, but inside, as shown,) while the low-test distillate starting at the other end of the other series passes over the other surface of said tubes, (outside, as shown.) Other known or suitable forms of heat-exchangers can be used instead.

In raising the fire test of burning-oil distillate with this apparatus the stream of low-test distillate passes over the heat-conducting walls of the heat-exchanger D—to wit, the walls of the tubes 24 in the several elements, 70 as shown—in the opposite direction to the stream of high-test distillate from the still C, so that in cooling the latter distillate the former is heated preliminarily to its introduction into the distilling and rectifying column A, say to 170° Fahrenheit, or more or less, according to circumstances, but most advantageously above the fire test to be secured in the distillate. The preliminarily-heated distillate fed into the upper part of the column 80 A descends through the same and supplies the body of distillate in the still C. This being supplied at one end by a stream and discharging at the other end in a stream travels after the manner of a river and is subjected 85 to free steam from the perforated coils 4 at intervals in its travel, while at the same time it is heated by the dry heat of the closed coils 3. This dry heat is not so important as the free steam and can be omitted, if preferred. The vapors resulting from the action of the free steam (aided by the dry heat of coils 3, if this be used) pass up through the column A and are repeatedly brought in contact with the stream of preliminarily-heated 90 distillate until they pass into and through the rectifying-column B, and so on to the condenser or condensers (not shown) or other apparatus. As the vapors rise the chief part, or, in fact, nearly all of the steam from the 95 perforated coils 4 is condensed, and mingling with the stream of preliminarily-heated distillate forms part of the stream with which the later rising vapors are continually brought into contact. The oil condensed 100 from the vapors also mingles with the stream, and as it descends is re-evaporated more or less, so that there are repeated condensations and re-evaporations, whereby the oil-vapors from the still C are rectified and a naphtha 105 suitably free from products fit for burning oil is obtained. The rising vapors, which are acted upon by the incoming distillate (as also by the hot water and oil from condensations higher up in the columns) as a condensing 110 agent, act in turn thereon to vaporize a portion of said distillate, the vapors thus formed mingling with those from the still C and being rectified along with them. Thus there is 115 in column A both distillation—to wit, of the incoming preliminarily-heated distillate—and rectification—to wit, of the vapors from the still C and from distillation of the incoming distillate in the column A. The vapors are subjected to a further rectification in 120 the column B.

The body of oil in the still C is limited relatively to the volume of steam admitted through the perforated coils, so that all the low-boiling products are removed in a short 130

time. It may be in a few minutes (under fifteen) and at any rate under two hours. The rectification in the columns A B serves to restore the products fit for burning oil which are evaporated at the same time by this rapid action of the free steam.

Assuming, by way of example, that the dams 18 are respectively twenty, twenty-four, twenty-eight, and thirty-two inches high and are located in a cylinder of five feet internal diameter at such places as to form compartments or pools each nine and a half feet in length, it is recommended to use pipe for coils as follows, namely: in the first compartment or pool, two hundred and thirty-eight feet of one-inch wrought-iron unperforated pipe for the closed coils and fifty-four feet of wrought-iron perforated pipe for the open coils; in the second compartment or pool, two hundred and four feet of one-inch unperforated pipe and thirty-six feet of one-inch perforated pipe; in the third compartment or pool, one hundred and fifty-three feet of one-inch unperforated pipe and twenty-seven feet of one-inch perforated pipe, and, in the last compartment, one hundred and nineteen feet of one-inch unperforated pipe and eighteen feet of one-inch perforated pipe. The perforations may be one-eighth-inch diameter, twelve inches between centers, and may be located on the under side of the pipes. The closed coils would best be supplied with exhaust, the open coils with live steam. The supply of low-test distillate is so regulated that enough to fill the oil-spaces of column A and still C will be introduced by pipe 2 every fifteen minutes, more or less. The supply of free steam is regulated to give oil of the desired fire test, and the temperature of the liquid in the jacket 9 is sufficiently below the boiling-point of water to prevent the passage of burning-oil hydrocarbons through the column B.

In raising its fire test about twenty per cent. of the low-test distillate may ordinarily, according to my experience, be separated as low-boiling products, but of course the percentage may vary. Thus if the composition of the low-test distillate should vary, either from difference in the crude oil or in the process of distillation, the removal of a greater or a less percentage of such products might be necessary in order to have burning oil of the same fire test; but a variation may also result from a variation in the manufacturer's wishes with respect to the grade of burning oil to be obtained. For some grades a lower fire test suffices than for others, and the manufacturer naturally desires to retain in the burning oil the lowest boiling products which would be consistent with the desired fire test. The temperature of the liquid in the jacket 9 would consequently be adjusted to prevent these latter products from passing over with those whose

presence in the burning oil would prevent it from having the desired fire test.

The temperatures in columns A and B are such as to effect the condensation therein of the chief part of the steam let into the perforated coils of still C. The temperature in the still C is about that of water-vapor under the barometric pressure inside of the still—to wit, about 212° Fahrenheit when the pressure in the still is not reduced below that of the outside atmosphere.

The horizontally-traveling body of oil in the still C being divided into a succession of communicating pools by the dams 18 the different parts are kept separate, and the dams being of diminishing height the pools are of diminishing depth, so that the free steam has less oil to pass up through—a condition which is believed to conduce to the efficiency of its action. In steaming the oil in the still C it is also an advantage and special improvement to decrease the volume of free steam per cubic foot of oil as the latter approaches the outlet 6^b, because, for one reason, the content of low-boiling products being less, it is not considered desirable to evaporate so large a proportion of the oil as in the earlier portion of the steaming operation, when the proportion of such products is greater.

As shown, the length of perforated steam-coil is greatest in the pool next the column A and decreases in order, being least in the pool next the outlet 6^b, and this decrease is in greater ratio than the decrease in the cubical contents of the pools, due to their diminishing depth toward said outlet. The volume of free steam decreases also, as shown, with reference to the square foot of exposed upper surface of the liquid being steamed, and this is considered advantageous, as modifying the evaporation in a desirable manner.

As said above, the chief part of the free steam admitted under the surface of the horizontally-traveling body of oil in still C is condensed in columns A and B and is thus returned to still C in the form of hot water, along with the oil from said columns, consisting in part of fresh distillate from the pipe 2 and in part of oil which has been evaporated in still C and column A and recondensed in columns A and B. In still C the water settles to the bottom and passes through the openings 19 at the bottoms of dams 18 into the compartment or pool, from which it is decanted by the draw-off 5. It could, of course, be withdrawn with the oil by allowing it to pass the last dam 18, for which purpose the pipe 20', having its open lower end near the bottom of the still and its open upper end inserted through the dam near the top, may be provided. By swinging the pipe 20' so that its lower end is brought nearer to or farther from the bottom of the

still C the depth of the water in the latter can be regulated.

It will of course be understood that the low-test distillate could be heated preliminarily to its introduction into the distilling and rectifying column A otherwise than by means of the high-test distillate; but in this case the economical advantage of imparting the heat of the outgoing high-test distillate 10 to the incoming low-test distillate would be lost, and the ability most perfectly to secure this economy is an important advantage attending the substitution of the continuous distillation of the present invention for the 15 periodical working of current practice. Further, the distillate introduced by pipe 2 is subjected to free steam in the column A, and thereby in part evaporated, and such subjection and evaporation are not necessarily 20 dependent upon the use of the still C; but the capacity of an apparatus of a given size for effective removal of the low-boiling products would be much less if dependence were had solely upon evaporation in column A than it 25 is when use is made of a special steaming appliance, (like the still C.)

The subjection of the vapors rising in column A to the returning stream of condensed oil mingled with hot water from the chief 30 portion of the free steam is not dependent upon the said stream containing also the low-test distillate, but it is advantageous to have it contain the same, and if it is desired to obtain such advantage the low-test distillate 35 should, as shown, be introduced at so high a point on the column A as in its descent to have a material influence on the rising vapors.

For using the present invention for distillation other than the separation of the low-boiling 40 products of burning-oil distillate from petroleum to raise the fire test of said distillate and for which said invention may be applicable, the skill of the workers in such other distillation will suffice in the light of the foregoing 45 description. It is not intended to assert, however, that said invention is superior to the current practice in all sorts of distillation, only it is intended to secure matters of my invention, hereinbefore described, which 50 may be new and useful as well otherwise, as in the special distillation for raising the fire test of burning-oil distillate for such other uses as the same may severally be applicable.

The liquid to be distilled of any suitable 55 kind can be introduced at the place or places described for the low-test distillate, the steam (in closed or perforated coils, or both) can be used at the temperatures and of the volume considered most suitable, and the outgoing residual liquid and the incoming 60 liquid to be distilled can be passed through a heat-exchanger in opposite directions, as described above, for the outgoing high-test distillate and the incoming low-test distillate, 65 the former being the residual liquid from the

special distillation to which the latter is subjected. The invention, however, concerns itself chiefly with the burning-oil distillate of petroleum, which distillate consists substantially of the fraction distilling between about 250° Fahrenheit and about 600° Fahrenheit, more or less, and which as obtained from the condenser of the still contains products with boiling-points so far below that of water that their presence in the finished burning oil 70 would render the latter too low in fire test, either generally or in special cases. When, therefore, in any of the hereinafter-written claims the expression "raising the fire test of burning-oil distillate" occurs, such claim is 80 intended to include only the special distillation in which said low-boiling products are removed from the said burning-oil distillate. In other claims more general expressions are used. Thus the expression "liquid to be distilled" includes, first, said burning-oil distillate; second, other petroleum or hydrocarbon oil, especially but not exclusively an oil containing hydrocarbons with boiling-points below that of water, while consisting mainly of 90 higher boiling products; third, any other appropriate liquid, especially, but not exclusively, such a liquid as contains substances with boiling-points below that of water.

The boiling-point of water in the hereinafter-written claims refers to its boiling-point under the barometric pressure in the still. This is intended to be practically that of the outside atmosphere, but it is not essential that it should be so.

I claim as my invention or discovery—

1. The process of raising the fire test of burning-oil distillate, consisting in partially evaporating the low-test distillate by contact of free steam therewith at about the boiling-point of water, cooling the resulting mixture of oil and water vapors gradually until the heavier oil-vapors and the chief part of the water-vapor are ultimately condensed and so separated from the vapors of the low-boiling 105 products which pass over, bringing the said mixture of oil and water vapors during said cooling thereof into repeated contact with the returning condensate of hot water and hot oil and also with a stream of low-test distillate preliminarily heated to a temperature 110 below the boiling-point of water and not lower than about 60° Fahrenheit below the same, and separating the oil and water of condensation from each other, substantially 115 as described.

2. The process of raising the fire test of burning-oil distillate, consisting in partially evaporating the low-test distillate by contact of free steam therewith at about the 125 boiling-point of water, cooling the resulting mixture of oil and water vapors gradually until the heavier oil-vapors and the chief part of the water-vapor are ultimately condensed and so separated from the vapors of the low- 130

boiling products which pass over, bringing the said mixture of oil and water vapors during said cooling thereof into repeated contact with the returning condensate of hot water and hot oil, and separating the oil and water of condensation from each other, substantially as described.

3. The process of raising the fire test of burning-oil distillate, consisting in partially evaporating the low-test distillate by contact therewith at about the boiling-point of water of free steam in sufficient volume to drive off the low-boiling products in a short time, to wit, under two hours, cooling the resulting mixture of oil and water vapors gradually until the heavier oil-vapors and the chief part of the water-vapor are ultimately condensed and so separated from the vapors of the low-boiling products which pass over, bringing the said mixture of oil and water vapors during said cooling thereof into repeated contact with the returning condensate of hot water and hot oil and also with a stream of low-test distillate, and separating the oil and water of condensation from each other, substantially as described.

4. The process of raising the fire test of burning-oil distillate, consisting in partially evaporating the low-test distillate by contact therewith at about the boiling-point of water of free steam in sufficient volume to drive off the low-boiling products in a short time, to wit, under two hours, cooling the resulting mixture of oil and water vapors gradually until the heavier oil-vapors and the chief part of the water-vapor are ultimately condensed and so separated from the vapors of the low-boiling products which pass over, bringing the said mixture of oil and water vapors during said cooling thereof into repeated contact with the returning condensate of hot water and hot oil, and separating the oil and water of condensation from each other, substantially as described.

5. The process of distilling petroleum or hydrocarbon oil containing hydrocarbons with boiling-points below that of water while consisting mainly of higher boiling products, consisting in admitting free steam at intervals below the surface of a horizontally-traveling body of such oil at about the boiling-point of water, cooling the resulting mixture of oil and water vapors until the heavier oil-vapors and the chief part of the water-vapor are condensed and so separated from the vapors of the low-boiling products which pass over, and separating the oil and water of condensation from each other, substantially as described.

6. The process of distilling petroleum or hydrocarbon oil containing hydrocarbons with boiling-points below that of water while consisting mainly of higher boiling products, consisting in admitting at intervals below the surface of a horizontally-traveling body

of such oil at about the boiling-point of water free steam in sufficient volume to drive off the low-boiling products in a short time, to wit, under two hours, cooling the resulting mixture of oil and water vapors until the heavier oil-vapors and the chief part of the water-vapor are condensed and so separated from the vapors of the low-boiling products which pass over, and separating the oil and water of condensation from each other, substantially as described.

7. In the distillation of liquids, the improvement consisting in delivering free steam at intervals below the surface of a horizontally-traveling body of the liquid to be distilled in such manner that the volume of so-delivered steam per cubic foot of liquid is lessened as the said liquid approaches the outlet therefor, substantially as described.

8. In the distillation of liquids, the improvement consisting in causing a body of the liquid to be distilled to travel horizontally and to diminish in depth as it approaches the outlet therefor, and delivering free steam at intervals below the surface of said body in such manner that the volume of so-delivered steam per cubic foot of liquid is lessened as said liquid approaches the outlet therefor, substantially as described.

9. In the distillation of liquids, the improvement consisting in causing a body of the liquid to be distilled to travel horizontally and to diminish in depth as it approaches the outlet therefor, and delivering free steam at intervals below the surface of said body in such manner that the volume of so-delivered steam per square foot of exposed upper surface of said liquid is lessened as said liquid approaches the outlet therefor, substantially as described.

10. The process of distillation, consisting in delivering free steam at intervals below the surface of a horizontally-traveling body of the liquid to be distilled in such manner that the volume of so-delivered steam per cubic foot of liquid is lessened as the said liquid approaches the outlet therefor, and cooling the resulting mixture of vapors so as to condense a portion of them while allowing another portion to pass over, substantially as described.

11. The process of distillation, consisting in causing a body of the liquid to be distilled to travel horizontally and to diminish in depth as it approaches the outlet therefor, delivering free steam at intervals below the surface of said body in such manner that the volume of so-delivered steam per cubic foot of liquid is lessened as said liquid approaches the outlet therefor, and cooling the resulting mixture of vapors so as to condense a portion of them while allowing another portion to pass over, substantially as described.

12. The process of distillation, consisting in causing a body of the liquid to be distilled

to travel horizontally and to diminish in depth as it approaches the outlet therefor, delivering free steam at intervals below the surface of said body in such manner that the volume 5 of so-delivered steam per square foot of exposed upper surface of said liquid is lessened as said liquid approaches the outlet therefor, and cooling the resulting mixture of vapors so as to condense a portion of them while allowing another portion to pass over, substantially as described.

13. For separating low-boiling products from petroleum or hydrocarbon oil which contains hydrocarbons with boiling-points 15 below that of water while consisting mainly of higher boiling products, the continuous process which consists in partially evaporating said oil by contact of free steam therewith, gradually cooling the evolved vapors, bringing 20 the body of said vapors into repeated contact with returning condensate, and adjusting the vapor-cooling to such extent below the boiling-point of water and the free-steam admission to such amount in excess of what 25 passes over with the hydrocarbons that the hydrocarbons passing over are mainly those with boiling-points below that of water and that the returning condensate is composed of the hot water from the chief part of said free 30 steam as well as of the hot oil of condensation, substantially as described.

14. For separating low-boiling products from petroleum or hydrocarbon oil which contains hydrocarbons with boiling points 35 below that of water while consisting mainly of higher boiling products, the continuous process which consists in partially evaporating said oil by contact of free steam therewith, gradually cooling the evolved vapors, bringing 40 the body of said vapors into repeated contact with a stream of said oil preliminarily heated by exchange of temperature with the oil from which the low-boiling products have been separated and mingled 45 with returning condensate, and adjusting the vapor-cooling to such extent below the boiling-point of water and the free-steam admission to such amount in excess of what passes 50 over with the hydrocarbons that the hydrocarbons passing over are mainly those with

boiling-points below that of water and that the returning condensate is composed of the hot water from the chief part of said free steam as well as of the hot oil of condensation, substantially as described. 55

15. For separating low-boiling products from petroleum or hydrocarbon oil which contains hydrocarbons with boiling-points below that of water while consisting mainly of higher boiling products, the continuous 60 process which consists in partially evaporating said oil by contact of free steam therewith, gradually cooling the evolved vapors, bringing the body of said vapors into repeated contact with returning condensate, 65 adjusting the vapor cooling to such extent below the boiling-point of water and the free-steam admission to such amount in excess of what passes over with the hydrocarbons that the hydrocarbons passing over are mainly 70 those with boiling-points below that of water and that the returning condensate is composed of the hot water from the chief part of said free steam as well as of the hot oil of condensation, and continuously separating the 75 oil and water from each other by settling and decantation, substantially as described.

16. For separating low-boiling products from petroleum or hydrocarbon oil containing hydrocarbons with boiling-points below 80 that of water while consisting mainly of higher boiling products, the continuous process, which is characterized by the partial evaporation of the said oil at about the boiling-point of water by contact of free steam therewith, and the repeated contact of the evolved vapors with the specified petroleum or hydrocarbon oil of a temperature below the boiling-point of water and not lower than about 60° Fahrenheit below the same mingled with returning condensate of hot oil and the hot water from the chief part of said free steam, substantially as described. 85 90

In testimony whereof I affix my signature in presence of two witnesses.

HERMAN FRASCH.
